UNITED STATES PATENT OFFICE.

SIMEON S JACKSON, OF BOSTON, MASSACHUSETTS, ASSIGNOR TO THE STAFFORD COMPANY, OF READVILLE, MASSACHUSETTS, A CORPORATION OF NEW JERSEY.

WEFT FEELER MECHANISM FOR LOOMS.

1,301,082.

Specification of Letters Patent.

Patented Apr. 15, 1919.

Application filed April 29, 1916. Serial No. 94,334.

To all whom it may concern:

Be it known that I, SIMEON S. JACKSON, a subject of Great Britain, residing at Readville, Boston, in the county of Suffolk, State 5 of Massachusetts, have invented a certain new and useful Improvement in Weft Feeler Mechanism for Looms, of which the following is a specification, reference being had therein to the accompanying drawings.

10 The invention has relation, in general, to the depletion-detecting mechanisms, commonly termed feeler mechanisms, which are employed in looms for the purpose of fore-stalling complete exhaustion of the supply 15 of weft or filling contained in the working shuttle upon the lay of a loom. These mechanisms, in general, are contrived to "indicate," or "call," or "initiate," as it variously is termed, a change in the operation of the 20 loom, upon detecting that the progressive depletion of the said supply has reached a stage decided upon as a minimum. The change involves in some cases automatic replenishing of the working supply of weft or 25 filling without stoppage of the loom; in other cases, it involves stoppage of the loom without automatic replenishment; in still others it involves stoppage of the loom, with automatic replenishment during the 30 stoppage, followed by automatic restarting of the loom.

The invention has relation more especially to feeler mechanisms of the measuring class. A feeler mechanism of this class is arranged 35 to call the prearranged change in the operation of the loom in which it is employed when, through its measuring action, it has detected that the residue of weft or filling upon the bobbin or other weft or filling-carrier in the shuttle has become reduced to the 40 predetermined minimum thickness.

The invention is embodied in measuring weft or filling feeler devices comprising a primary contact-member constituted by a 45 feeler-member or finger that is moved by the pressure of the shuttle-contained weft or filling-supply, at least during the earlier stages of said supply; a secondary, assisting or coadjutor, contact-member constituted by 50 a second feeler-member or finger that is given by the pressure of the said weft or filling-supply a movement differentially correlated with that of the primary contact-member; a controller-rest that is actuated 55 through the movement of the said primary

contact-member, and in addition controlled by the said secondary or coadjutor contact-member and arranged to coact therewith in measuring the differential; and a controller for the devices that call a change in the operation of the loom. With these elements I combine means which, so long as the portion of the shuttle-contained weft or filling-supply that acts against the primary contact-member exceeds a certain diameter, operates 60 through the controller to prevent the parts that are controlled by the controller from being called into action. This means consists, preferably, in governing means for the controller-rest, coöperating with the latter in 65 manner to secure the stated result. This feature of invention prevents a cylindrical full-diameter portion of the mass of weft or filling that is contained in the shuttle from having the same effect as the practically emptied 70 filling-carrier in bringing about a change in the operation of the loom. The means of governing the controller-rest, and the specific mode of operation thereof, vary in the 75 case of different embodiments of the principles of the invention.

Briefly stated; during the earlier stages of the weft or filling-supply the controller-rest governor governs the controller-rest, and thereby the controller, in such manner that 80 the parts which are controlled by the controller are prevented from being called prematurely into action to call a change in the 85 operation of the loom. Such means renders the working of the feeler devices an idle ac- 90 tion at each movement throughout the earlier stages of the weft-supply, and until only a small amount of weft or filling slightly exceeding the predetermined minimum remains within the shuttle. After the controller-rest 95 governing means has ceased to act, the secondary, assisting, or coadjutor contact-member coöperates with the controller-rest in the functions of (1) measuring the final 100 stages of the weft-supply, (2) detecting reduction of the final residue to the predetermined minimum, and (3) through the controller rendering the parts that are controlled by the latter operative to bring about a change in the operation of the loom.

The invention is capable of being reduced to practice in various ways and by various mechanical constructions.

In the drawings,—

Figure 1 is a perspective view of an illus- 110

trative embodiment of the invention in connection with devices of well-known character for calling a change in the operation of a loom.

5 Fig. 2 is an end elevation of the outer portion of the feeler mechanism of Fig. 1, with certain parts in section.

10 Fig. 3 is a plan view of the parts that are represented in Fig. 1, only a portion of the length of the controller-rockshaft being shown.

15 Figs. 4 and 5 are views similar to Figs. 2 and 3, but with the addition of the weft-hammer, catch, and a portion of the arm at the inner end of the controller-rockshaft, and illustrating the action at the beat-up during the full-diameter stage of the supply of weft or filling contained in the shuttle on the lay.

20 Figs. 6 and 7 are views similar to Figs. 4 and 5, but illustrating the action at the beat-up during the tapered residue stage.

25 Figs. 8 and 9 are views illustrating the action at the beat-up when the predetermined minimum residue has been reached.

30 Having reference to the drawings,

In the illustrative embodiment that is shown in the said figures, the contact-members constituted by the feeler-members or fingers 1 and 2 are, for convenience, on the order of those shown and described in U. S. Letters Patent No. 940,600 granted Nov. 16, 1909 upon my application. That is to say, they are in this instance in the form of slides which are mounted side by side in guides provided in upstanding portions of a small feeler-stand 32. Substantially as in the said Letters Patent, they are held in rearward positions, normally, by means of expanding spiral springs 31 and 41, sur-

35 rounding their forwardly-extending stems or shanks 3 and 4, and confined between the upstanding guide-lug 32^a at the front end of said feeler-stand and the front ends of the body-portions of the feeler-members or fingers. The said rearward positions are de-

40 termined through the contact of lateral pro-

jections 1^a, 2^a, from the bodies of the feeler-

members or fingers with the upstanding lug

32^b at the rear end of the said feeler-stand.

45 As usual in feeler mechanisms, the rear ends of the feeler-members or fingers 1 and 2 are designed to enter the shuttle on the lay from the front as the lay goes forward. Both thereof are designed to be acted upon by the

50 weft or filling-mass. In their normal posi-

tions the feeler-members or fingers await the

pressure or blow of the contents of the shut-

tle against their rear ends. They both are

moved forward a short distance by such

60 pressure or blow.

A special feature of the feeler-members or fingers 1, 2, is the fact that, while they occupy the said normal positions, the feeler-member or finger 1 projects a little farther

65 rearward (as for instance about one-eighth

of an inch) than the feeler-member or finger 2, as indicated in Fig. 3. The difference is somewhat greater than the predetermined "minimum" thickness, *i. e.*, the thickness of the final remainder of weft or filling in the filling-carrier in the shuttle when the change is called. It corresponds with the bevel, inclination, or slope of the tapering conical end of the filling-mass as represented in Fig. 5. Note also Fig. 7. 75 Consequently, a cylindrical portion of the wound mass of weft or filling within the shuttle presented to the two feeler-members or fingers at the beat-up of the lay as in Fig. 5 will cause the member 1 to begin to move 80 forward before member 2 does, and will shift member 1 relative to member 2 (one-eighth of an inch).

The form, construction, mode of mounting the feeler-members or fingers, and manner 85 of applying spring-pressure, may vary more or less in practice. It is not essential in all cases that they should be slides.

The controller-rest 7 is a two-part finger that is hung by means of its body-portion 90 upon a pivot-pin 9 projecting transversely from an upstanding portion 10 at the front end of the feeler-member 1. Thereby the controller-rest is connected pivotally at its forward end with the feeler-member 1, and 95 supported at such end. The downturned tip 71 of the rear end of the controller-rest lies normally upon the top surface of the feeler-member 2 at the rear of the rear end of an opening 5 in the latter feeler-member. By 100 such surface of feeler-member 2 the controller-rest is supported normally at its free end, as in Fig. 2, for instance. So long as the free end of the controller-rest is thus supported, it is locked by the secondary 105 feeler-member 2. When feeler-member 1 is displaced forward relative to feeler-member 2 far enough to carry the tip 71 forward beyond the rear end of opening 5, and into a 110 position over said opening, the controller-rest is unlocked from feeler-member 2. The two parts of the controller-rest overlap each other for portions of their length, and are connected together by means of a clamping screw 7^a, the stem of which occupies a longi- 115 tudinal slot 7^b in the rear part of the controller-rest. By means of an adjusting screw 7^c working in upstanding lugs with which the two parts of the controller-rest are furnished, the rear part may be adjusted upon 120 and relative to the said body-portion 8, so as to vary the extent to which the tip 71 projects rearward beyond the rear end of the opening 5 in the secondary feeler-member. By this adjustment the extent of relative 125 displacement of feeler-member 1 with respect to feeler-member 2 necessary to carry tip 71 forward beyond the rear end of opening 5 and thereby unlock the controller from feeler-member 2 may be varied.

The controller 44 consists mainly of a rockshaft that is mounted in bearings 441, 441, Fig. 1, provided in connection with the supporting stand 442 on which the small 5 feeler-stand 32 is mounted. For coöperation with controller-rest 7, the outer end of the controller rockshaft has mounted thereon fixedly an arm 13 formed with a crank-pin 11 which lies upon the controller-rest 7. 10 Through the engagement between the controller-rest and the crank-pin the crank-pin 11 is supported and the controller is locked from turning in the direction of the arrow shown in Fig. 1 upon its rockshaft, so long 15 as the controller-rest itself remains locked through the engagement of its tip 71 with the top surface of feeler-member 2.

The controller operatively controls the devices by which a change in the operation of 20 the loom is called, by means of an arm 443 mounted fixedly on the inner end of the controller rockshaft and provided with a crank-pin 444. The said crank-pin works in a slot 445 in a catch or dog 21 of usual 25 character forming an element of the said devices. The said catch or dog in this instance is hinged at 22, Fig. 1, to the arm 23 forming a part of devices for controlling loom-stopping mechanism and mechanism 30 for automatically effecting replenishment and restarting the loom. It is furnished with an engaging portion, shown in Fig. 1 as a lateral spur 24, and in Figs. 4, 6 and 8 as a tooth or shoulder 24^a, for coaction 35 with a suitable striker. In the present instance, as ordinarily is the case in practice, the weft-hammer 26 is utilized as the striker, it being provided with a shoulder 25 adapted to engage the said spur, tooth or shoulder 40 in case the catch or dog should occupy its lowered position as the weft-hammer goes forward, for the purpose of pushing the catch or dog and arm forward and thereby bringing about the change in the operation 45 of the loom.

While the controller-rest remains locked by the secondary feeler-member, that is to say normally, the controller is locked in a position which holds the catch or dog elevated so that its engaging portion 24 or 24^a 50 is above the path in which the shoulder 25 of the weft-hammer travels as the weft-hammer swings forward. While this remains the case, the weft-hammer makes its forward stroke without engaging with the catch. The catch or dog in Fig. 1 is in the 55 said elevated position, although on account of the perspective this fact does not show with entire clearness. The weight of the 60 catch 21 and of crank-arms 443 and 13, and the coöperating tension of a spring 33 connected with the controller rockshaft, tend to turn the controller in the direction indicated by the arrow thereon in Fig. 1, and 65 operate to turn the controller in such direc-

tion when it is free to turn, to thereby lower the catch 21 into position to be engaged by the shoulder 25 of the weft-hammer. This turning of the controller is prevented as long as the controller-rest remains locked as 70 aforesaid. An elongated arch or bail 72 rising from the controller-rest 7 extends above and over the crank-pin 11 of the controller, for convenience in keeping the two parts in working relations with each other, and also 75 for enabling the weaver to lift the controller-rest so as to withdraw its tip 71 from the opening 5, when it is desired to do so manually, simply by taking hold of some convenient part of the controller and rock- 80 ing the latter in the direction opposite to that indicated by the arrow in Fig. 1.

The particular character and construction of the controller and the devices controlled thereby for calling a change in the operation of a loom are not material, so far as the invention is concerned.

The controller-rest governor 15 of this embodiment is a small cross-bar that is fixed upon the rear portion of the stand 32, between the tops of the feeler-members and the under side of the body-portion 8 of the controller-rest 7. Such cross-bar serves incidentally the secondary function of keeping the feeler-members from rising out of their guideways in the said portion of stand 32. For coöperation with the controller-rest governor, the body-portion of the controller-rest is formed at its under side with a cam-projection 14, the said cam-projection having its forward portion inclined to facilitate riding up upon the governor 15 as the forward movement of feeler-member 1 carries the controller-rest from its position in Fig. 2 to one placing the said cam-projection momentarily upon the top of said governor, as in Fig. 4, for instance.

Having reference now to the operation of the devices which have been described, and the principles which are involved in such 110 operation,—

As is well known, the weft or filling yarn carried by a filling-carrier occupying a loom-shuttle is drawn off from the said carrier in the direction of the length of the 115 latter past the free end or tip of the filling-carrier, and issues from the shuttle through a delivery-eye with which the shuttle is furnished near the adjacent end thereof. To provide for the yarn being thus drawn off past the free end or tip of the filling-carrier, weft or filling is wound upon filling-carriers with a so-called cone-wind, as shown in various views of the drawing, 120 namely in successive layers resembling conical or tapering shells, one outside another, until the required length of wound mass is produced. The said wound mass is cylindrical exteriorly for the main portion of its length, and has a conical end facing toward 130

the tip of the filling-carrier. See Fig. 5. When the spiral coils or turns constituting the exposed tapering layer of the cone-shaped end are drawn off, another similar 5 layer is uncovered, and so on. The progressive withdrawal of the said layers shortens the wound mass progressively until the 10 yarn has been paid off from the filling-carrier back to the head or base-end of the latter. Fig. 7 shows the tapering residue which remains when the paying-out of the 15 weft or filling has progressed so far that the main cylindrical portion of the wound mass has disappeared, and Fig. 9 shows a small wound portion of weft or filling which 20 remains upon the filling-carrier just prior to complete exhaustion.

When the shuttle is supplied with a filled filling-carrier, a cylindrical portion of the 25 wound mass of weft or filling is pressed against the feeling ends of the two feeler-members 1 and 2 at every feeling action, as illustrated in Figs. 4 and 5, during the preliminary stage of the weft or filling-supply 30 that continues while the portion of the filling-mass that touches the feeling ends of the feeling-members is of full diameter. This preliminary stage, which I call the full-diameter stage, is a stage of long duration. 35 It continues from the time when a fresh filling-carrier loaded nearly to its tip with weft or filling is brought into action, to the time when the mass has become reduced in length so that the base of the cone or taper 40 of the remainder or residue is just about to be caused to extend to a point which as the lay goes forward will touch the feeling end of the feeler-member 1. The feeler-members 1 and 2 are located in such a position in the 45 loom that they feel against the filling-mass at the usual place for feeling action, namely close to the enlarged head or base of the filling-carrier. Consequently, as indicated in Fig. 7, a very large proportion of the filling- 50 mass will have been paid out before the cone or taper of the remainder or residue is exposed to feeler-member 1.

In each feeling action during the full-diameter stage the contact of the cylindrical 55 filling-mass with the rearwardly-projecting feeler-member 1 moves the latter member forward relative to feeler-member 2, thereby shifting the controller-rest forward so as to move its tip 71 forward past the rear end of 60 opening 5, thereby unlocking the controller-rest from feeler-member 2. This would permit the controller to operate to call the change in the operation of the loom if provision were not made thereagainst. Such 65 change would be unnecessary. A change called at a time when the filling-mass occupying the shuttle is of anything like the proportions of that shown by Figs. 5 and 6, or in fact at any time during the full-diameter 70 stage, would be objectionable and undesirable.

Accordingly, during the full-diameter stage, the controller-rest governor 15 is in action as shown in Fig. 4. A full or substantially full-diameter of weft or filling-supply operates at the beat-up of the lay to 75 drive feeler-member 1 and the controller-rest 7 so far forward that the cam-projection 14 rides up on the controller-rest governor 15 as shown in the view. Consequently, at the beat-up, the controller-rest is 80 locked in an elevated position, and thereby the controller is locked in a position in which the engaging portion of the catch or dog 21 is above and clear of the path of the shoulder 25 of the forwardly advancing weft-hammer. 85

As a result of the action of the controller-rest governor during the full-diameter stage, the differential movement of the feeler-members by which the feeler-member 1 is driven forward first, so that it moves forward an 85 amount represented by the extent to which it normally projects rearward beyond the feeler-member 2, before the feeler-member 2 begins to move, is without either useful or harmful result or consequence. It occurs 90 merely as an outcome of the difference in the position of the two feeling ends, and the movement of the controller-rest tip 71 into a position over the opening 5 of the feeler-member 2 as in Fig. 4, is taken care of by 95 means of the controller-rest governor so that the controller-rest is given an elevated position.

When the weft or filling begins to pay out from the portion of the wound mass that 100 makes contact with feeler-member 1, the extent to which such member is pushed forward will diminish and the difference between the strokes of the two feeler-members will decrease until the tapered residue stage in the 105 consumption or paying-out of the weft or filling from the shuttle is reached. Figs. 6 and 7 show what I term the tapered residue stage. It will be perceived that in this stage, at the beat-up of the lay, the largest diameter of the residue or remainder of the filling-mass is presented against the feeler-member 2, while the conical or tapering portion of the said residue or remainder is presented against the feeler-member 1. A 110 smaller diameter, therefore, is presented to the feeler-member 1 than the diameter which is presented to the feeler-member 2. The surface which is presented to the feeler-member 2 is in this instance assumed to be 115 about an eighth of an inch, more or less, farther forward than the portion of the cone or taper which is presented to the feeler-member 1. To compensate for this difference in diameters, the rear end of 120 feeler-member 1 is arranged to project normally a corresponding distance farther rearward than the rear end of feeler-member or finger 2, as stated hereinbefore. Consequently, during the tapered residue stage, 125 130

as the filling-mass is carried forward toward the feeler-members it will touch the feeling ends of the two members simultaneously, or approximately so. For a time, therefore, the 5 two feeler-members will be driven forward in unison by the pressure of the filling-mass against their feeling ends, with the tip of controller-rest 7 lying upon the top surface of the feeler-member 2 at the rear of opening 5 and supported thereby. While this continues, the controller is locked by feeler-member 2 in the position in which it supports the catch 21 out of the path of the engaging shoulder of the weft-hammer. At 10 this stage, the decreased diameter of the portion of the filling mass which acts against the feeler-member 1 reduces the extent of the forward movement of said feeler-member and the controller-rest 7 pivoted thereto, so that the cam-projection 14 of the controller-rest does not touch the controller-rest governor 15. The controller-rest governor does not act and is not needed to act.

As the filling continues to be drawn off 25 from the "tapered residue" the various diameters of the latter become smaller. The cone or taper disappears, and shortly the surface of the filling carrier itself in line with the feeler-member 1 is uncovered and 30 at the beat-up makes contact with the said feeler-member, as in Fig. 9, which shows the minimum stage, while the small bunch of filling still remaining opposite the feeler-member 2, and wound upon the filling-carrier at such point expressly to serve at this 35 stage in the consumption of the filling-mass, makes contact with the feeler-member 2, as in Figs. 8 and 9. A measuring action begins just as soon as the difference in position 40 forwardly, of the two surfaces touched by the two feeler-members, begins to grow less than the normal extent of projection of the feeler-member 1 rearward of feeler-member 2. It is accompanied by a resumption 45 of the differential movement of the two feelers, the feeler-member 1 leading the feeler-member 2 as the two feeler-members are driven forward at each feeling action. This differential movement produces at each 50 successive beat-up a movement of the tip 71 of controller-rest 7 forward upon the top surface of feeler-member 2, and toward the edge of the opening 5. The relative movement increases in extent at each successive 55 beat-up, in proportion as the remaining filling diminishes in diameter, and consequently the tip 71 approaches closer and closer toward the edge of the opening 5, until finally, when the relative diameters of 60 the filling-carrier where it touches feeler-member 1, and of the remaining bunch of filling, become such that the relative movement of the feeler-member 1 forward with respect to feeler-member 2 carries the said 65 tip 71 of the controller-rest 7 off the edge of

the opening 5, as in Figs. 8 and 9, the controller-rest and controller will be unlocked, and under the influence of the spring 33 and gravity the controller will rock so as to place the engaging portion 24 or 24^a of 70 catch 21 in position to be engaged by shoulder 25 of the weft-hammer. Thereby the said catch and the arm 23 will be operated so as to bring about the prearranged change in the operation of the loom. 75

Through adjustment of the tip-carrying part of the controller-rest by means of screw 7^c so as to cause tip 71 to lap rearward of the rear edge of opening 5 more or less, the release of the controller-rest may be caused 80 to take place sooner or later, according as it is desired to leave more or less filling upon the filling-carrier when the change is called.

Ordinarily in the operation of a loom having the just described feeler mechanism applied thereto, while the lay is rearward the weft-hammer also occupies a rearward position with the shoulder 25 a short distance, somewhere about a quarter of an inch, to the rear of the engaging portion 24 or 24^a of the 90 catch 21. The weft-hammer remains in this position while the lay goes forward. As the lay approaches front center the filling-mass contained in the shuttle in the shuttle-box of the lay strikes the rear ends of the feeler-members and drives them forward, the contact with the full diameter of filling-mass taking place under the usual adjustments when the lay is somewhere about a half an inch or three-eighths of an inch back from 100 the most forward point reached by it. When the lay is about a quarter of an inch back from the said most forward point, the weft-hammer begins to move forward. The contact of the cam-projection 14 of the controller-rest with the cross-bar 15 in the final portion of the movement of the lay throws the controller-rest upward, gives a quick turn to the controller, and also throws the catch 21 upward, and the continued forward 105 movement of the weft-hammer carries the shoulder 25 forward under the engaging portion 24 or 24^a of the catch 21 while the catch is thus elevated. As the weft-hammer goes forward under the engaging portion 24 or 110 24^a the top of the weft-hammer behind the shoulder 25 bears against the underside of the said engaging portion so as to support the catch until the rearward movement of the weft-hammer withdraws the shoulder 25 115 out from under the spur. The shoulder 25 passes forward under the engaging portion 24 or 24^a of the catch after the cam-projection 14 has passed forward upon the controller-rest governor 15 and while it is either 120 resting upon the top of the said governor or poised by momentum slightly above the same. The weft-hammer follows the lay rearward, but the top of the weft-hammer does not pass out from under the spur of the 130

catch, and continues to support the catch and the controller, until the lay has moved rearward a considerable distance.

The controller-rest governor has two functions. One thereof is to prevent the feeler devices from acting to call a change in the operation of the loom at any time during the "full diameter" stage (shown in Figs. 4 and 5) of the filling-mass on the carrier in the shuttle. The other function is to raise the controller-rest sufficiently high as it goes forward with the feeler-member 1 to insure that, as the said feeler-member and the controller-rest are driven rearward again by the action of the spring 31 as the lay and shuttle retreat rearwardly, the tip 71 of the controller-rest shall land on the top surface of the feeler-member 2 at the rear of the opening 5, and not drop into the said opening.

What is claimed as the invention is,—

1. Weft or filling feeler devices comprising a primary contact-member constituted by a feeler-member or finger that is moved by the pressure of the shuttle-contained weft or filling-supply, at least during the earlier stages of said supply; a secondary, assisting or coadjutor, contact-member constituted by a second feeler-member or finger that is given by the pressure of said weft or filling-supply a movement differentially correlated with that of the primary contact-member; a controller-rest that is actuated through the movement of the said primary contact-member, and in addition controlled by the said secondary or coadjutor contact-member and arranged to coat therewith in measuring the differential; and a controller for the devices that call a change in the operation of the loom.

2. Weft or filling feeler devices comprising a primary contact-member constituted by a feeler-member or finger that is moved by the pressure of the shuttle-contained weft or filling-supply, at least during the earlier stages of said supply; a secondary, assisting or coadjutor, contact-member constituted by a second feeler-member or finger that is given by the pressure of said weft or filling-supply a movement differentially correlated with that of the primary contact-member; a controller-rest that is actuated through the movement of the said primary contact-member, and in addition controlled by the said secondary or coadjutor contact-member and arranged to coat therewith in measuring the differential; and a controller for the devices that call a change in the operation of the loom, and having combined therewith means which, so long as the portion of weft or filling-supply that acts against the primary contact-member exceeds a certain diameter, operates through the controller to prevent the devices that

are controlled by the latter from being called into action.

3. Weft or filling feeler devices comprising a primary contact-member constituted by a feeler-member or finger that is moved by the pressure of the shuttle-contained weft or filling-supply, at least during the earlier stages of said supply; a secondary, assisting or coadjutor, contact-member constituted by a second feeler-member or finger that is given by the pressure of said weft or filling-supply a movement differentially correlated with that of the primary contact-member; a controller-rest that is actuated through the movement of the said primary contact-member, and in addition controlled by the said secondary or coadjutor contact-member and arranged to coat therewith in measuring the differential; and a controller for the devices that call a change in the operation of the loom, and having combined therewith governing means for the controller-rest whereby so long as the portion of weft or filling-supply that acts against the primary contact-member exceeds a certain diameter the devices that are controlled by the controller are prevented from being called into action.

4. Weft-feeler mechanism comprising devices for calling a change, a controller therefor, a feeler-member, a controller-rest actuated by the said feeler-member, a secondary feeler-member controlling said controller-rest, and means unconnected with said secondary feeler-member acting through said controller-rest to render said devices inoperative to call a change while the diameter of the filling-mass exceeds a predetermined amount.

5. Weft-feeler mechanism comprising devices for calling a change, a controller for such devices, a feeler-member, a controller-rest actuated by the said feeler-member, a secondary feeler-member controlling said controller-rest, and means unconnected with said secondary feeler-member acting through said controller-rest to render said devices inoperative to call a change by movement of the first-mentioned feeler-member exceeding a predetermined amount.

6. Weft-feeler mechanism comprising a controller for the devices for calling a change in the operation of a loom, a contact member moved at least during the earlier stages of the said weft-supply by pressure of the working weft-supply, a controller-rest accompanying said contact-member in the movement of the latter, a controller-rest governor which at each movement of said contact-member exceeding a predetermined extent renders the working of the feeler-devices an idle action, and a coadjutor given a movement correlated with that of the said contact-member, and cooperating with said

controller-rest in measuring the final stages of the weft-supply, detecting reduction to the predetermined minimum, and rendering the controller operative.

- 5 7. Weft-feeler mechanism comprising devices for calling a change, a controller therefor, a feeler-member, a controller-rest actuated by the said feeler-member, and a secondary feeler-member controlling said controller-rest, and including means engaging with said controller-rest to render said devices inoperative to call a change when the movement communicated by the filling-mass to the first-mentioned feeler-member exceeds
- 10 15 a predetermined amount.
8. Weft-feeler mechanism comprising de-

vices for calling a change, a controller for such devices, a feeler-member, a controller-rest actuated by the said feeler-member, a secondary feeler-member controlling said controller-rest, and means acting through said controller-rest to render said devices inoperative to call a change by filling-produced movement of the first-mentioned feeler-member exceeding a predetermined amount.

In testimony whereof I affix my signature in presence of two witnesses.

SIMEON S. JACKSON.
